FASTENING MEANS FOR GARMENTS, AND
MORE PARTICULARLY DIAPERS

Jessie C. Condylis, Chicago, Ill.

Application October 7, 1949, Serial No. 120,111

8 Claims. (Cl. 128—284)

1

This invention relates to fastening means for garments and more particularly diapers for infants.

A principal object of the invention is the elimination of safety pins, buttons and such more or less extraneous elements, and in place thereof providing fabric fastening elements which may be integral, homogeneous or homologous with the fabric of the garment while at the same time permitting extension or contraction of the garment for adaptation to size of the wearer.

A particular embodiment of the invention as applied to infants' diapers is herein specifically disclosed but it is intended to be understood that the invention is adaptable to other garments as for example men's pajamas, women's slips, and the like.

Objects and advantages will be more readily apparent from the following description, taken together with the accompanying drawings, of two illustrative embodiments of the invention, and in which drawings—

Figure 1 is a plan view showing a diaper sheet with which the present invention is associated;

Figure 2 is a folded view of the diaper sheet of Fig. 1 showing the fastening elements in normal position preparatory to use;

Figure 3 is a view of the panel formed by the diaper as in Fig. 2 again folded upon itself in its next step of application;

Figure 4 shows an intermediate step in the fastening process, this and subsequent views being somewhat enlarged;

Figure 5 shows the completed fastening;

Figure 6 shows an adaptation to a smaller vertical size for the diaper;

Figure 7 shows an adaptation to a smaller size both vertically and circumferentially;

Figure 8 shows an application of the invention to another type of garment; and

Figure 9 is a plan view of the structure of Fig. 8.

Referring in detail to the illustrative construction shown in the drawings, numeral 11 indicates a sheet of suitable diaper material and which may be creased vertically as at 12, 13 and 14 to be folded to panel form as shown in Fig. 2. For this purpose the crease 12 may be brought into conjunction with the crease 14 and with the edge 15 in conjunction with the crease 13. Next, the sheet is inverted and the edge 16 brought into adjacency with the crease 13 and edge 15, thus providing a multi-layer panel form for the diaper.

On the panel formed between the creases 13 and 14 and adjacent the lower margin thereof may be provided a fabric loop 17 for a purpose presently pointed out.

2

In accordance with the present invention, adjacent the upper margins of the panel along each vertical edge, in this instance secured to opposite edges of the panel portion formed between the creases 13 and 14 are a pair of flaps 18 and 19. Similarly secured to the garment, and thus directly or indirectly to one of the flaps, is a strap 20, in this instance secured with the flap 19.

Adjacent the upper margins of the flaps are 10 a series of perforations which are here termed "button-holes" because of their similarity thereto in construction and appearance, although, as already mentioned, the present invention does not contemplate the use of buttons. It will be understood that the term "button-hole" is here used for convenience of description to refer to any suitable aperture or perforation for the purpose.

Adjacent the upper edge of the flap 18 are a 20 series of longitudinally or circumferentially aligned button-holes 21, 22, 23 and 24, and similarly along the upper margin of the flap 19 is a series of similar button holes 25, 26, 27 and 28. The holes 21 and 25 are at the outer or end tongues 26a and 27a respectively of flaps 18 and 25 19, these tongues constituting the free apex of the somewhat triangular flaps 18 and 19 respectively, the bases of which 28a and 29 respectively are secured as by stitching to diaper sheet 11 adjacent the creases 13 and 14 respectively as already referred to. Thus the button-holes already mentioned are aligned along the margins of what may be termed the altitudes 30 and 31 respectively of the flaps which in turn are somewhat coincident or coplanar with the upper edge 32 of the diaper sheet.

What may be termed the hypotenuse (33 and 34 respectively) of the flaps completes the somewhat right angular definition of the flaps and other button holes are provided in the margins of 40 the flaps adjacent the lower end of each hypotenuse. Thus, in the flap 18 are button-holes 35 and 36 and in the flap 19 button-holes 37 and 38. The button-holes of these pairs of button-holes 35—36 and 37—38 are not aligned longitudinally but are spaced apart vertically in the flaps and are also desirably staggered laterally to correspond in general with the hypotenuse of each flap.

Farther down on the panel of the diaper and 50 nearer the lower edge 39 thereof, but spaced vertically of the loop 17 which is adjacent this edge, are pairs of tabs, one pair being 40—41 and the other 42—43. The pair of tabs 40—41 may be integrally fabricated and sewn as by 55 an intermediate transverse stitch 43a to the diaper material; this stitch being somewhat coin-

cident with the crease 13. Similarly the pair of tabs 42—43 may be sewn by a stitch 44 coincident with the crease 14. The tabs of each pair could of course be separately secured to the panel instead of integral.

The use of the diaper and operation of the fastening means will next be described.

The diaper having been folded to panel form as in Fig. 2, it may be placed between the legs of the infant and then folded upon itself as shown in Fig. 3 at which time the upper edge 32 and initially lower edge 39 are brought into somewhat the same plane about the waist of the infant. At this time the loop 17 and tabs 40—41 and 42—43 are at the front of the garment and the flaps 18 and 19 at the rear, but the latter ready to be brought around to the front of the garment as indicated by the position of the flap 18 (Fig. 3). The tongue 26a of the flap 18 is shown placed through the loop 17.

Next, as shown in Fig. 4, the flap 19 is brought around to the front of the diaper and the tongue portion 26a of the flap 18 is passed through one of the button-holes, say 26 in this instance, of the flap 19, this flap having its tongue 27a also placed in the loop 17. Next, as shown in Fig. 5, the strap 20 is likewise brought around to the front of the garment and its free end passed through the button-hole 21 of the flap 18, this button-hole being in the tongue 26a of this flap which has been passed through the hole 26. The garment is then securely fastened about the waist and will not come apart until the strap 20 is completely withdrawn from the button-hole 21. The free end of the strap 20 is preferably but not necessarily in the loop 17. Since at least the tongues 26a and 27a are in the loop 17, the front part of the diaper is prevented from slipping down.

To further secure the diaper, and particularly about the legs of the infant, the tabs 40—41 and 42—43 are next shown secured. As seen in Fig. 5, the tab 40 has been passed through the button-hole 35 and the tab 41 passed through a button-hole 45 in the tab 40. Similarly, the tab 42 has been passed through the button-hole 37 and the tab 43 passed through the button-hole 46 in the tab 42. Thus the front part of the diaper, about the legs of the infant, are securely fastened to the flaps 18 and 19 in that region.

As seen in Fig. 6, if it is desired to shorten the vertical height of the diaper from the fasteners to the crotch, the tabs may be fastened in the upper button-holes 36 and 38 respectively. Here, the front of the garment is moved up, but the loop 17 is long enough vertically to accommodate this and still receive tongues 26a and 27a therethrough.

As shown in Fig. 7, the diaper may be adapted to a very small child by being reduced both vertically and circumferentially, i. e., from the fastener to the crotch, and about the waist. In this arrangement, to reduce the distance from the fastener to the crotch, the front of the diaper is moved up so that the loop 17 is entirely above the flaps 18 and 19 and these are fastened together below the loop 17. To reduce the distance about the waist or contract the diaper the tongue 26a may be passed through the button-hole 27 in the flap 19 which will cause the flap 19 to overlap the flap 18 to a greater degree (Fig. 7). In this arrangement the strap 20 extends to a greater degree through and beyond the button-hole 21 as shown. In the Fig. 7 arrangement, the tabs may, if desired, be left unfastened, since

there is sufficient overlap of the flaps to maintain the diaper snugly about the legs of the infant. Similarly, button-hole 28 may be used for further contraction.

If preferred, for simplicity of manufacture, the button-holes 22, 23, 24 in the flap 18 and the button-hole 25 in the flap 19 might be omitted, but the flaps have been here shown alike in the arrangement of button-holes so as to be interchangeably overlapped with either the flap 18 underneath and the tongue 26a passing through the button-hole 26 of flap 19, as here shown, or, reversely, with the flap 19 underneath and the tongue 27a passing through the button-hole 22 of the flap 18. In such latter case (however, not here shown) the strap 20 would be passed through the button-hole 25 of the tongue 27a.

Turning now to another application of the invention and as seen in Figs. 8 and 9, the present fastening means might be employed for any garment holding means such as a shoulder fastener across the top of a woman's slip, the upper margins of which are indicated at 47 and 48. In this case, a belt or strap 49 is stitched as at 50 to the garment margin 47 and a pair of tabs 51—52 secured as by stitch 53 to the garment margin 48. The strap 49 has its free end passed through a button-hole 54 in the tab 51, and then the tab 52 is passed through the button-hole 55 in the strap 49. To selectively shorten this fastening, the strap has aligned button-holes 56 and 57 and it may be pulled through the button-hole 54 until either the button-hole 56 or the button-hole 57 has gone through the button hole 54, whereupon the tab 52 may be put through button-hole 56 or button-hole 57 as the case may be.

In any application here shown, or other applications which will occur to those apprised of the invention, the fastening means comprises a fabric or fabric-like material having integral therewith a first member (such as the flap 19 or the tab 51) having a first perforation therein (button-hole 26 or button-hole 54), a second member or fabric or fabric-like material (tongue 26a or strap 49) passing through said first perforation and having a second perforation therein (the button-hole 21 or button-hole 55) in the portion thereof passed through the first perforation, and a third member (strap 20 or tab 52) secured to one of said first mentioned members and passing through the second perforation.

Similarly, flap 18 is a member having a perforation 35, the tab 40 is a member passing through 35 and having a second perforation 45, and the tab 41 is a third member passing through 45.

It is intended to be understood that the word fabric as here used includes cloth and may include similar materials having the somewhat limp character of cloth.

Manifestly, it is not intended that the invention be limited to details of construction shown for purposes of exemplification, and, furthermore, it may not be essential that all features of the invention be used conjointly, since various combinations or subcombinations may at times be advantageously employed. Such changes may be made as fall within the scope of the appended claims without departing from the invention.

What is here claimed is:

1. In a diaper, the combination with a sheet foldable upon itself to panel form, a pair of flaps at opposite upper edges of the panel, a button-hole in the outer upper end of each flap, one of

the flaps being adapted to have its outer end pass through the button-hole in the other flap, and a strap secured to one of the flaps and passing through the button-hole of the flap passed through the other flap, a pair of tabs at each lower edge of the panel, the panel being adapted to be folded on itself to bring the tabs into the vicinity of the flap, and a lower button hole in each flap, one tab of each pair being adapted to pass through said last mentioned button-hole, and said last mentioned tab having a button-hole therein through which the other tab of the pair is passed through thereafter.

2. The structure of claim 1 wherein there are a plurality of button-holes at each place mentioned in the flaps.

3. In a diaper, the combination with a sheet foldable upon itself to panel form, a pair of flaps at opposite upper edges of the panel, a button-hole in the outer upper end of each flap, one of the flaps being adapted to have its outer end pass through the button-hole in the other flap, and a strap secured to one of the flaps and passing through the button-hole of the flap passed through the other flap.

4. The structure of claim 3 wherein there are a plurality of button holes in at least one of the flaps.

5. Fastening means for garments or the like, comprising a first part having a first button-hole therein, a second part having a limp end portion for passing through said first button-hole and having a second button-hole in the said end portion at least a portion of which passes through

5
10
15

said first button-hole, and a member secured to one of said parts for passing through said second button-hole.

6. The structure of claim 5 wherein the button-holes extend lengthwise of said portions.

7. In a diaper, the combination with a body panel of a pair of flaps at opposite upper edges of the panel, a plurality of circumferentially aligned button-holes in the outer upper end of a first of said flaps, the other flap being adapted to have its outer end pass through one of the button-holes in the said first flap, a button-hole in the end of said other flap which is passed through the button-hole in said first flap, and a strap secured to said first flap for passing through the button-hole of said other flap, to secure the diaper in body-encircling form.

8. The structure of claim 7 wherein the lower edge of the panel is provided with a loop and the flaps are adapted to be passed through said loop when the diaper is in use.

JESSIE C. CONDYLIS.
